MOUNTING AND DECORATIVE MEANS FOR
PANELS, PANES, AND THE LIKE

Lorne C. Smith, Chicago, Ill.

Application April 26, 1947, Serial No. 744,259

7 Claims. (Cl. 20—56.4)

1

This invention relates to mounting and decorative means for panels, panes and the like; and more particularly to such means providing for the use of a face strip comprising a plurality of short sections.

In mounting panels, panes and the like, as for example the glass pane in a display window, in a support such as a window frame, it is often desirable to provide a face strip around the edge of the pane. My improved face strip is particularly adapted to be utilized as a decorative member as well as a portion of the mounting means, and may have an ornamental design, a name, etc., on its face.

In my earlier patents, as for example Patents 1,873,349 and 1,873,350 issued August 23, 1932, I have disclosed a means for mounting such a pane, panel or other member of sheet material in a support or frame, this mounting means including a face strip on the front side of the sheet member. Such mounting means also generally includes one or more members for engaging the face of the sheet member and means for securing said members in clamping relation to the sheet. Since mounting means of this type are often used to mount relatively large panes or panels, it has been the practice in the past to produce the sheet engaging members and the face strip in long sections, as for example sections 15 to 18 feet in length. Such long sections have been objectionable in that they are difficult to handle and uneconomical to ship from place to place. In addition, in utilizing such sections, particularly sections of the face strip, where a neat and ornamental appearance is desired there has been much waste in material encountered, for after cutting the long sections to the outside dimensions of the sheet member, it often happens that there are several pieces of substantial length left over. Since it has been undesirable from a decorative standpoint to piece these face strip sections, and since the sections are often too short to be used in a single piece, much of this material has been wasted in the past. This waste has been particularly objectionable since the face strip is usually relatively expensive.

In addition it is impractical to mold or die-cast a 15 to 18 foot section of face strip material, and as a consequence in the past these sections have been rolled. This method of manufacture places a substantial limitation upon the ornamentation which may be placed upon such members since it is impractical to roll many decorative designs and it is impossible to roll embossed designs, names, etc.

2

I have provided and am here disclosing and claiming mounting and decorative means of this type wherein I provide face strip members each having a short length, and I construct the ends of each face strip member to permit unobvious abutment with other strip members. Several advantages stem from this construction. In the first place the waste in utilizing the relatively expensive face strip is cut down to an almost negligible amount; in the second place the short face strip sections are easily handled and may be easily and economically shipped from place to place; and in the third place such short face strip members may be molded or die-cast with any type of design thereon, as for example an embossed pattern or a name. I prefer to construct the ends of each face strip member with an overlapping joint which follows the design on the member so that when the members are assembled in abutment with each other the joint may be entirely concealed from view, giving the appearance of a single piece face strip.

Furthermore, I provide a locking means so that the face strip members may be easily assembled, particularly around the sides and top of the panel, pane or other sheet member. I also provide an inside molding strip of greater length than each of the face strip members, this molding strip serving to secure the strip members in place. The construction of this type of molding strip is such that it may be coiled when it is shipped, thereby obviating the shipping problems mentioned heretofore.

Other features and advantages of my invention will be apparent from the following specification and the drawings in which:

Fig. 1 is an elevation of a portion of a sheet member mounted in a support including mounting and decorative means comprising my invention;

Fig. 2 is a fragmentary section through the structure of Fig. 1 along the line 2—2 of Fig. 1;

Fig. 3 is a vertical section along the line 3—3 of Fig. 2;

Fig. 4 is an extended horizontal section along the line 4—4 of Fig. 2;

Fig. 5 is a partly sectional elevation of the top retaining mold forming a part of my invention; and

Fig. 6 is a fragmentary section through the ornamental face strip member taken on the line 6—6 of Fig. 4.

Referring now to the drawings, a sheet member 10, which is illustrated as comprising a glass pane, but which might comprise a panel, as for

example a display panel, or any similar member of sheet material, is shown mounted in a support 11. While this support is illustrated as comprising a window sill or frame having a base portion 11a and a rear portion 11b, it will be understood that any supporting structure within which the sheet member 10 may be mounted is envisioned within the scope of my invention.

Means are provided for securing the sheet member to the support, these means being shown most clearly in Fig. 2 and comprising a first clamping member 12 adapted to engage one side of the sheet member 10, and a second clamping member 13 having a portion adapted to engage the other side of the said sheet. The member 12 may be in the form of a long strip, and has a rear vertical portion 12a (as the parts appear in Figure 2) which abuts against the support member 11b and may be secured to said support member if desired by screws or other means not shown. The top of the clamping member 12 extends forwardly and upwardly at 12b and engages one side of the sheet member 10, while the bottom of the clamping member 12 extends underneath and forwardly of the sheet member, and terminates in an upwardly overturned flange 12c. A channel 12d is formed in the member 12 and into this channel a cushion member 14 is positioned to provide a base support for the sheet member 10.

The second clamping member 13 comprises a clip which is preferably about 1½ inches wide, and has a sheet engaging portion 13a. On either side of the portion 13a the clip is provided with an outwardly turned flange 13b which is spaced from the face of the sheet member, each of said flanges having a projecting lug 13b' on the rear side thereof. A nut 15 is secured to the clamping member 12, as by welding or otherwise, and a stud 16 extends through the clamping member 13 and is threaded into said nut in order to secure the clamping members in clamping relation to said sheet member. I prefer to provide the second clamping members or clips 13 at about 10 inch intervals along the edges of the sheet member.

A plurality of short face strip members, as the members 17a and 17b, are provided, these members being constructed in accordance with my invention in short sections, preferably though not necessarily each approximately 2 feet long. Short members of such a size are easily handled, economically shipped, and may be used in mounting a sheet member and making the necessary cuts at the corners of such a member with a very minimum of waste. In addition, short members as provided by my invention may be molded or die-cast rather than rolled, and when manufactured in this manner the members may be provided with ornamentation in the form of an embossed design, a name, or numerous other designs which are impossible to provide when the face strip members are manufactured by a rolling process. As illustrated in the drawings the face strip 17 is provided with a raised ornamental design 17' in the form of a plurality of ellipses, sometimes termed an "egg and dart" design, a design of this nature being impossible to produce by a rolling process of manufacture.

The ends of each of the short face strip members are constructed to permit unobvious abutment with other strip members, the construction being illustrated in Fig. 6 and preferably comprising an overlapping joint 18. I prefer that this joint be constructed to follow the ornamental design 17' on the face strip member, and with

this construction I am able to provide an unobvious joint between said members which is entirely concealed from view, and gives the appearance of a face strip member which is continuous across the entire sheet member.

Each of the face strip members, as the members 17a and 17b, are so constructed that the outer edge is folded back at 17b, to form a channel which cooperates with the overturned flange 12c formed in the forward edge of the clamping member 12 so that the outside edge of the strip members may be locked to the clamping member as the apparatus is assembled, and the inner edge terminates in a vertical flange 17b''. The terms "outside edge" and "inside edge" as applied to said strip members are used to indicate the location of these edges with reference to the sheet member 10 when the apparatus is assembled. Thus as shown in Fig. 2 the outside edge 17b' and the inside edge 17b'' are located in respective outside and inside arrangement when the sheet member 10 is framed in its support 11.

A particular advantage of providing a lock between the outside edge of the face strip members 25 and the clamping member is that such construction results in much greater ease of assembly, particularly in assembling the mounting means around the vertical sides and the top portion of the sheet member.

30 An inside molding 20 comprising a channel-shaped member of substantially greater length than each of said face strip members is also provided, the term "inside" again being intended to indicate the location of this molding with reference to the edges of the sheet member 10 when the parts are assembled. The inside molding 20 is of such construction that it may readily be coiled when it is shipped, and consequently rather than constructing such molding in short lengths, 40 I prefer to provide such molding in continuous pieces of substantially greater length than each of the face strip members. One wall of the channel formed by the molding has notches 20a cut into it, said notches being adapted to cooperate with the sheet engaging portion 13a of the second clamping member 13, the wall of the channel which has such notches in it being adapted to be inserted between the flanges 13b of said second clamping member and the face of the sheet member 10. The channel wall is also provided with detents 20b adapted to cooperate with the lugs 13b' to frictionally hold the top molding 20 in engagement with the outwardly turned flanges 13b of the clamping member 13. The opposite channel wall of the member 20 engages the vertically flanged inside edge 17b'' of the face strip members and fastens said strip members to the member 13.

In assembling my apparatus, the first clamping member 12 is mounted on the frame or support 11 for the sheet member, said clamping member being preferably screwed or otherwise fastened to said support. The sheet member 10 is then placed in position, being cushioned along its outer edges on the member 14, and the second clamping members 13 are then placed in position and secured in clamping relationship to said sheet by means of the stud 16. The face strip members 17 are then placed in position, the locking engagement between the outside edge of said members and the flange 12c on the forwardly projecting edge of the clamping member 12 preventing the strip members from falling out of position, particularly on the vertical sides and the top portion of the frame structure. The over-

lapping joints 18 between each of the face strip members provide an unobvious abutment which gives the appearance of a continuous face strip throughout the length of each side of the sheet member. Finally, the inside molding 20, which is of substantially greater length than each of the face strip members and preferably extends in one continuous piece the entire length of each side of the panel, is snapped into place, the notches 20a cooperating with the sheet engaging portions 13a, and the detents 20b in the wall of the channel engaging the projecting lugs 13b' in the clamping member 13 to frictionally hold the parts together. Inasmuch as each face member is locked at its outside edge to the clamping member 12 and is fastened at its inside edge to the clamping member 13 by means of the inside molding 20, as clearly illustrated in Fig. 2, the apparatus will be held securely in place, and because of the concealed joints 18 and the presence of the continuous molding 20 at the point where the joints would otherwise be most visible, the face members will give the appearance of a continuous face strip.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Apparatus of the character described for mounting a sheet member in a support, including: means for securing said sheet member to said support; a plurality of short face strip members each having its ends constructed to permit unobvious abutment with other strip members; and a molding of substantially greater length than each of said strip members, said molding providing means for positively locking said strip members to said first mentioned means.

2. Apparatus of the character described for mounting a sheet member in a support, including: means for securing said sheet member to said support; a plurality of short face strip members, each having its ends constructed to permit abutment with other strip members to form an unobvious overlapping joint between said members; and a molding adapted to cooperate with said securing means and strip members said molding forming the sole fastening means along one side of the strip members to fasten that side of the strip members to the securing means, said molding comprising a continuous piece of substantially greater length than each of said strip members.

3. Apparatus of the character described for mounting a sheet member in a support, including: a first clamping member adapted in normal use to engage one side of said sheet; a second clamping member having a portion adapted in normal use to engage the other side of said sheet and a portion spaced from said sheet; means for securing said members in clamping relation to said sheet; a plurality of short face strip members, each having its ends constructed to permit unobvious abutment with other strip members; and an inside molding of substantially greater length than each of said strip members, said molding being adapted to cooperate with said spaced portion and sheet engaging portion to fasten said strip members positively to said second clamping member.

4. Apparatus of the character described for

mounting a sheet member in a support, including: a first clamping member adapted to engage one side of said sheet; a second clamping member having a portion adapted to engage the other side of said sheet and a flange spaced from said sheet and extending parallel thereto; means for securing said members in clamping engagement with said sheet; a plurality of short face strip members, each having its ends constructed to permit unobvious abutment with other strip members; an inside molding comprising a continuous channel-shaped member of substantially greater length than each of said strip members, a portion of said inside molding being adapted to be inserted between said flange and sheet to fasten said strip members to said second clamping member; and means for holding said inside molding in engagement with said flange near the outer edge thereof.

5. Apparatus of the character described for mounting a sheet member in a support, including: a first clamping member adapted in normal use to be secured to said support and to engage one side of said sheet; a second clamping member having a portion adapted in normal use to engage the other side of said sheet and a flange spaced from said sheet and extending parallel thereto; means for securing said members in clamping engagement with said sheet; a plurality of short, ornamented face strip members, each strip member having its ends constructed to permit abutment with other strip members to form an unobvious overlapping joint between said members, said joint following said ornamentation; an inside molding comprising a continuous channel-shaped member of substantially greater length than each of said strip members, one wall of said molding having a notch therein adapted to cooperate with the sheet engaging portion of said second clamping member, said wall having the notch being adapted to be inserted between said flange and sheet to fasten said strip members to said second clamping member; and means comprising a lug and a detent for frictionally holding said inside molding in engagement with said flange.

6. Apparatus of the character described for mounting a sheet member in a support, including: a first clamping member adapted to engage one side of said sheet; a second clamping member adapted to engage the other side of said sheet; means for securing said members in clamping engagement with said sheet; a plurality of short face strip members each having its ends constructed to permit unobvious abutment with other strip members; an inside molding of substantially greater length than each of said strip members, said inside molding being adapted to fasten the inside edge of said strip members to one of said clamping members, and said strip members and one of said clamping members having cooperating hooking portions for positively locking the outside edge of said strip members to said last mentioned clamping member.

7. Apparatus of the character described for mounting a sheet member in a support, including: a first clamping member adapted in normal use to engage one side of said sheet; a second clamping member having a portion adapted in normal use to engage the other side of said sheet and a flange spaced from said sheet; means for securing said members in clamping engagement with said sheet; a plurality of short face strip members, each having its ends constructed to permit unobvious abutment with other strip mem-

bers; an inside molding comprising a continuous channel-shaped member of substantially greater length than each of said strip members, a portion of said inside molding being adapted to be inserted between said flange and sheet to fasten the inside edge of said strip members to said second clamping member; means for holding said inside molding in engagement with said flange, said strip members and said first clamping member having cooperating hooking portions for positively locking the outside edge of said strip members to said first clamping member.
